(**) Term: **15 Years**

(21) Appl. No.: **35/502,481**

(57) **CLAIM**

(22) Filed: **Aug. 24, 2016**

The ornamental design for a windscreen wiper blade, as shown and described.

(80) **Hague Agreement Data**

Int. Filing Date: **Aug. 24, 2016**

DESCRIPTION

Int. Reg. No.: **DM/092426**

1. Windscreen wiper blade

1.1 : Perspective

1.2 : Front

1.3 : Back

1.4 : Left

1.5 : Right

1.6 : Top

1.7 : Bottom

Int. Reg. Date: **Aug. 24, 2016**

The broken lines form no part of the claimed design; the one-dot dash lines represent unclaimed boundary lines and form no part of claimed design; the parallel two-dot dash lines are separation lines, showing that any portion of the article beyond what is shown forms no part of the claimed design.

Int. Reg. Pub. Date: **Feb. 24, 2017**
